UNITED STATES PATENT OFFICE.

FRANCISZEK STANKOWSKI, OF BALTIMORE, MARYLAND.

BARREL-SMOKING OVEN.

1,230,050.

Specification of Letters Patent. Patented June 12, 1917.

Application filed December 11, 1916. Serial No. 136,318.

To all whom it may concern:

Be it known that I, FRANCISZEK STANKOWSKI, subject of the Czar of Russia, residing at Baltimore, in the county of Baltimore City and State of Maryland, have invented certain new and useful Improvements in Barrel-Smoking Ovens, of which the following is a specification.

This invention relates to the art of coo-
10 pering and has special reference to a barrel
smoking oven.

As usually practised in cooper shops the barrels, after the staves and heads are assembled and hooped, are subject to a bath 15 of hot smoke for the purpose of closing the wood pores after thoroughly drying the barrels.

This operation is performed in the open shop or in ovens in the shop with the result 20 that the smoke spreads through the entire shop thus working great inconvenience to the workmen and detriment to their health. Moreover, this method can not insure a proper bathing in dense smoke owing to the 25 freedom with which the smoke will escape from the vicinity of the barrels.

One important object of the invention is to provide an improved form of smoking oven so proportioned and constructed as to 30 effect the bathing of the barrels in a body of dense smoke without the smoke finding its way into the shop, the apparatus being arranged to hold the smoke close to the barrels and permitting its escape from the vicinity 35 of the barrels but slowly.

Furthermore, the methods now used do not produce a smoke of requisite density owing to the fact that too great a quantity of oxygen (from the air) is permitted to 40 combine with the carbonaceous elements of the fuel employed and the proper imperfect combustion is not effected.

A second important object of the invention is to provide an improved construction 45 of oven so proportioned and arranged as to produce such imperfect combustion as will result in the production of a body of dense smoke in the vicinity of the barrels to be smoked.

50 A third important object of the invention is to provide such means of introducing the air, which is necessary for such combustion, to the oven in such manner as to have very little effect in causing movement of the 55 smoke away from the vicinity of the barrels being treated.

With the above and other objects in view, as will be hereinafter apparent the invention consists in general of certain novel details of construction and combinations of parts hereinafter fully described, illustrated in the accompanying drawing, and specifically claimed.

In the accompanying drawing, like characters of reference indicate like parts in the several views, and:

Figure 1 is a front view of the oven.

Fig. 2 is a vertical median section thereof.

Fig. 3 is a section on the line 3—3 of

Fig. 2. 70

Fig. 4 is a section on the line 4—4 of Fig. 2.

Fig. 5 is a section on the line 5—5 of Fig. 2.

In carrying out this invention I have 75 found that there are certain definite relationships existing between the cross sectional areas of different parts of the device which must be closely adhered to in order to produce the desired result. I have also found 80 that it is important that the fresh air be introduced at the top of what I term the smoke chamber and that the top of said chamber be not only arranged at a particular angle but that it be provided, in addition with draft retarding means to check too great motion in the body of smoke produced by the inflowing air.

To this end I provide a smoke chamber 10 having a front wall 11 provided with an 90 access opening 12 which is closed hermetically by doors 13 when the barrels B are being smoked. The bottom 14 of this chamber forms a rectangular hearth on which the fuel is placed, the barrels being supported on brick stools 15.

The rear wall 16 of this chamber preferably forms the outer wall of the building and is provided with a flue opening from the outside as at 17 and extending vertically up to the top of the rear wall the vertical portion being shown at 18. The top of the chamber starts level with the inner flue opening and extends upwardly and rearwardly at an angle of 45° so that the 105 brick courses may form a series of inverted steps 19 the treads and risers of which are equal. I have found this feature to be of peculiar importance as otherwise too rapid an upward flow of smoke will result or, if 110 the angle is made less, the damping effect will be too great and the fire will go out.

From the top extends upward a smoke flue 20 having its back wall continuous with the back wall of the flue 18 and of a cross sectional area equal to one-ninth the hearth area, the cross sectional area of the flue 18 being one-sixth that of the flue 20.

Under these circumstances the air entering through the flue 18 will flow in part down to the hearth and in part up the flue 20. I have found that with these proportions this air is just sufficient to produce the required density of smoke and will move downward so quietly as to replace the gases of combustion so gradually that there will always be, during operation, a proper smoke bath surrounding the barrels B.

There has thus been provided a simple and efficient device of the kind described and for the purpose specified.

Having thus described the invention, what is claimed as new, is:—

1. A barrel smoking oven comprising a chamber having a hearth, hermetically closing doors at the front of the chamber, an air inlet flue opening into the upper part of the chamber, and a smoke flue extending upward from the top of said chamber and having a cross sectional area not greater than one-ninth the floor area of the chamber,

ber, the air inlet flue having a cross sectional area not greater than one-sixth the cross sectional area of the smoke flue.

2. A barrel smoking oven comprising a chamber having a floor constituting a hearth, doors hermetically closing the front of said chamber, a smoke flue extending upward from the top of the chamber and having a cross sectional area not greater than one-ninth the floor area of the hearth, the top of said chamber being inclined from the front to the rear at an angle of not more than 45° to the horizontal, said top being angularly corrugated transversely of the chamber, the chamber having a back wall provided with an air inlet flue opening from the outside near the bottom of the wall and extending vertically upward in the wall to open on a level with the lower edge of the chamber top, said air inlet flue having a cross sectional area not greater than one-sixth the cross sectional area of the smoke flue.

In testimony whereof I affix my signature in the presence of two witnesses.

FRANCISZEK STANKOWSKI.
